[57] CLAIM

The ornamental design for a coupler for structural tubes or the like, substantially as shown.

DESCRIPTION

FIG. 1 is a side elevational view of a coupler for structural tubes or the like showing my new design;

FIG. 2 is a left end elevational view thereof;

FIG. 3 is a right end elevational view thereof; and

FIG. 4 is a cross sectional view taken along line 4—4 of FIG. 1.

FIG.1**FIG.2****FIG.3****FIG. 4**
